CABINET AND THE LIKE

Harry L. Skoogh, Jamestown, N. Y., assignor to
Art Metal Construction Company, Jamestown,
N. Y.

Application April 11, 1934, Serial No. 720,091

9 Claims. (Cl. 312—140)

This invention relates to improvements in cabinets or cases such, for example, as the cabinets employed in museums for housing and protecting specimens, and the walls of which are formed in whole or in part of separate and preferably detachably mounted panels or glass paneled frames to display the contents of the cabinets. Such cabinets may, for example, comprise front, back and end walls each composed of one or more such

10 glass paneled frames which are secured together or to the frame posts at the corners of the cabinet, and other points where the adjacent edges of two panels may meet.

It is important in such cabinets to construct and assemble the parts so as to insure tight, dust and vermin-proof joints between the edges of the several panels or frames and the parts against which they are intended to seat or abut and also between the bars of the frame of each panel at the corners of the frame, and it is, of course, desirable to accomplish this by a construction which provides a cabinet of pleasing design or attractive appearance but which nevertheless is of strong and rigid construction.

25 One purpose of my invention is to accomplish these results.

Other objects of the invention are to provide a strong and rigid corner construction for the panel frames which will insure tight joints between the 30 meeting ends of the frame bars at the corners of the frames; also to provide reliable means of simple construction for detachably or removably securing the panels or frames in place in connection with each other or with the frame posts of the cabinet; and also to improve the construction of cabinets or cases of the character mentioned in the other respects hereinafter described and set forth in the claims.

In the accompanying drawings which illustrate 40 only those portions of a cabinet necessary to an understanding of the invention:

Fig. 1 is an edge elevation of a removable panel of a cabinet embodying my invention.

Fig. 2 is a fragmentary, inside elevation of the 45 upper end thereof.

Fig. 3 is a front elevation of the upper portion of the cabinet showing one front panel in place and an adjacent panel removed.

Fig. 4 is a perspective view of a lower front 50 corner of the cabinet, the front panel being removed.

Fig. 5 is a fragmentary edge elevation similar to Fig. 1 on a larger scale.

Fig. 6 is an inside elevation of one corner of 55 a glass paneled frame showing the position of

the side bar before it has been forced tightly up against the end of the top frame bar.

Fig. 7 is a similar view, partly in section, showing the frame bars in their final position.

Fig. 8 is a sectional view through a corner of the cabinet, as on line 8—8, Fig. 4, showing the joint between the meeting edges of adjacent panels which extend perpendicularly to each other.

Fig. 9 is a section through one edge of a removable panel on an enlarged scale on line 9—9, Fig. 1.

Fig. 10 is a section on line 10—10, Fig. 3, showing the adjacent edges of two removable front panels secured in place.

Fig. 11 is a section on line 11—11, Fig. 7, looking in the direction of the arrows.

Fig. 12 is an elevation of one of the frame corner braces detached.

Fig. 13 is a bottom plan view thereof.

Figs. 14 and 15 are fragmentary transverse sections on an enlarged scale illustrating respectively the relative position of the locking bar for locking a panel to the cabinet, before and after the locking movement of the bar.

Fig. 16 is a fragmentary vertical section on line 16—16 Fig. 14.

15 represents the bottom or bottom panel of the cabinet, 16 one of the end walls or panels, and 17 and 18 two front panels each consisting of a framed glass plate. The front panel 17, which is preferably made removable to afford access to the interior of the cabinet, as shown, comprises a glass plate 19 secured in a frame formed by upright side bars and end bars, 20 30 representing the side bars and 21 the top end bar of this frame. These bars, which are alike in shape, are formed with grooved inner edges to receive the edges of the glass plate, which is retained in the grooves with tight joints between the glass and the bars by suitable packing means

35 22 inserted between the walls of the grooves and the glass plate. The meeting ends of the top and side frame bars 21 and 20 are bevelled to form miter joints at the corners of the frame, and these bevelled ends are secured so as to form 40 tight corner joints by right-angle corner braces 23 each having a vertical leg which is secured in a longitudinal channel 24 in the side bar 20 and a horizontal leg which is secured in the longitudinal channel 24 in the top bar 21. Preferably, the frame bars 20, 21, have bevelled outer edge faces 25 which provide bevelled outer marginal edges for the panel 17 and these faces 25 intersect

45 the channels 24, leaving an inwardly projecting 50

55 26 which is received in a channel 27 in the side bar 20. The top bar 21 is secured to the side bar 20 by a lock 28 which is secured to the top end bar 21 and the side bar 20.

Fig. 28 is a fragmentary edge elevation similar to Fig. 1 on a larger scale.

Fig. 29 is an inside elevation of one corner of a glass paneled frame showing the position of

flange or edge 26 (see Figs. 8-10) at the mouth of each channel which confines the leg of the corner brace in the channel and prevents its disengagement therefrom except by pulling the leg 5 out lengthwise.

The legs of the corner brace 23 are secured in the channels of the meeting frame bars 20, 21, by set screws 27, Figs. 6 and 7, turning in screw threaded holes 28 in the legs of the corner brace. 10 These holes pass through the legs of the brace at inclinations such that their inner ends are nearer to the angle of the brace than their outer ends so that when the set screws are screwed in, their inner ends will engage the walls of the 15 channels in which the legs are located, and the tightening of the screws will act to draw the legs lengthwise into the channels. In securing the frame bars together, they are slipped over the legs of the corner brace and moved endwise to bring their bevelled ends close together. Then by tightening the set screws, the legs of the corner brace will be forced lengthwise in the channels of the two bars, thereby pressing the bevelled ends of the bars into tight engagement or abutment with each other. 25

The frame bars are jointed together at the corners of the panel frame by similar corner braces secured in the same manner, and similar corner constructions may be employed in the other panel 30 frames of the cabinet. The corner braces have bevelled edges 29 substantially flush with the bevel faces 25 so as to permit the bevelled edge of one frame to abut flat against the corresponding bevelled edge of an adjacent frame of the cabinet as 35 shown in Fig. 8. Preferably the threaded holes 28 for the set screws are also inclined so as to extend substantially perpendicularly to these bevelled edges 29 of the braces. This inclination of the holes facilitates the insertion and tightening 40 of the set screws, and by reason thereof, the tightening of the screws draws the legs of the corner brace tightly against the channel flanges 26 of the frame bars. The set screws thus act not only 45 to draw the meeting bevelled ends of the bars into close contact but also to shift the two frame bars 20, 21, at each corner of the frame transversely so that the outer or front faces of the bars will lie flush with each other in the same plane. 50

Each of the glass paneled frames of the cabinet 55 may be of this same construction.

As above explained, the marginal edges 25 of the front panel 17 shown, are bevelled, and these bevelled edges, at the outer, upright edge of the panel and at the top and bottom edges thereof 60 are adapted to seat against corresponding bevelled edges on the end panel 16 and the top and bottom walls or panels of the cabinet respectively, while the bevelled edge of the remaining upright edge of the panel 17 is adapted to 65 fit against a corresponding bevelled edge 31 of a fixed post 32 at the front of the cabinet between the ends thereof. Preferably, the front panel 17 is removably secured tightly against said opposing bevelled edges of the cabinet by 70 vertical locking bars 33, one of which is arranged to move longitudinally in the channel 24 in each side frame bar of this panel. These locking bars (see Figs. 9 and 10) are confined in the channels against lateral displacement by the inwardly projecting flanges 26 of the channels. Each locking bar 33 is provided with an outwardly or rearwardly projecting flange 34, and this flange of one bar is adapted to enter the channel 24 in the front bar of the end panel while the flange 75 of the other locking bar enters a similar channel

35 in the post 32 of the cabinet. The flange 34 of each locking bar is provided, preferably near its upper and lower ends, and also therebetween, with lateral projections 36 which are adapted, when the front panel is moved inwardly 5 toward its bevelled seat on the cabinet to pass into the channels of the end panel bar and the post 32 through notches 37 in the front flanges 26 of these channels. The projections 36 preferably have bevelled top and bottom edges 38, connected by parallel inner and outer vertical edges 39.

When a front panel is moved into closing relation to the cabinet and the projections 36 are thereby passed through the notches 37, the front 15 vertical edges 38 of the projections will be located a slight distance forward of the plane of the inner front walls of the flanges 26 of the channels 35 in the cabinet posts 32, as shown in Figs. 14 and 16. In this position the inner, upper 20 corners of the notches 37 overhang the front upper corners of the projections formed by the angles between the bevelled top edges 38 and the front vertical edges 39. At this time there may be a slight clearance between the bevelled 25 edges 25 of the panel and the opposed bevelled edges 31 of the cabinet, as shown in exaggerated form in Fig. 14. Upon shifting the locking bars 33 upwardly however, the upper front corners of the projections 36 will encounter the inner overhanging corners of the notches 37 and as the 30 projections continue on into the channels 35, the projections will be cammed inwardly with their front upright edges 39 bearing against the inner front faces of the flanges 26. In this way 35 the locking bars are forced rearwardly so as to thereby cam or wedge the front panel inwardly tightly against its bevelled seat on the cabinet, and the forcible engagement of the front edges of the projections 36 with the inner faces of 40 the flanges 26 will secure the front panel tightly and firmly in place.

While the locking bars are shown in spaced relation to the panel bars in Fig. 10 for the sake of clearness, the actual relation of the parts 45 is more properly illustrated in Figs. 14 and 15, which figures respectively show the position of the locking bar before and after the camming action above described.

The locking bars can be moved vertically for 50 thus locking the panel in place by any suitable bar shifting instrumentalities, but preferably, for this purpose, each locking bar is provided with a toothed rack 40 adapted to be engaged by the pinion teeth of a key 41 which is adapted to 55 be inserted through and turned in a keyhole 42, Fig. 9, extending into the side bar 20 through the front face thereof. By inserting the keys into these holes in engagement with the toothed racks of the locking bars and turning the keys, the locking bars can be moved upwardly or downwardly to lock the panel in place and release it to permit its removal. The keys also serve as handles for the panel when fastening or removing the same. 60

Each locking bar moves in its guide channel between the legs of the corner braces which extend into the opposite ends of the channel, and spaces must be left between the ends of the bar and the corner brace legs to allow for the movement of the bar. In order to cover or close these 70 spaces, the locking bar is formed with end extensions 43 of reduced thickness at its opposite ends which overlap the legs of the corner braces and cover the spaces, see Figs. 5 and 6. 75

The channels 24 in those frame bars of the panels which are not occupied by movable locking bars 33, may be filled between the corner braces by bars similar to the locking bars. Such a bar is shown at 44 in the top frame bars in Figs. 2, 5 and 6. These bars 44 form tongues which enter the channels of the abutting frame bars and aid in forming tight, rigid joints between the panels or members of the cabinet.

10 I claim as my invention:

1. A cabinet frame construction comprising frame bars having adjacent ends with longitudinal channels, a joint brace having legs each extending lengthwise in the channel of one of said bars, and a set screw in a threaded hole in each leg of said brace and engaging the bar in which the leg is located, said set screws diverging from each other outwardly from their inner ends whereby the adjacent ends of said bars are forced into close contact by tightening said set screws.

2. A cabinet frame construction comprising frame bars having adjacent ends with longitudinal channels, a joint brace having legs each extending lengthwise in the channel of one of said bars and confined therein against lateral displacement, and a set screw in a threaded hole in each leg of said brace and engaging the bar in which the leg is located, said set screws diverging from each other outwardly from their inner ends whereby the adjacent ends of said bars are forced into close contact by tightening said set screws.

3. A cabinet frame construction comprising frame bars having adjacent ends with longitudinal channels, a joint brace having legs each extending lengthwise in the channel of one of said bars, and a set screw passing through a transverse threaded hole in each leg of said brace with its inner end engaging the bar in which the leg is located, said set screws diverging from each other outwardly from their inner ends whereby the adjacent ends of said bars are forced into close contact by tightening said set screws.

4. A cabinet frame construction comprising frame bars extending at an angle to each other and having adjacent mitered ends and channels extending longitudinally in said bars from said ends, a corner brace having legs each extending lengthwise in the channel of one of said bars, and a set screw in a threaded hole in each leg of said brace and engaging the bar in which the leg is located, said set screws diverging from each other outwardly from their inner ends, whereby the mitered ends of said bars are forced into close contact by tightening said set screws.

5. A cabinet frame construction comprising frame bars extending at an angle to each other and having adjacent mitered ends and bevelled outer edges and having channels extending longitudinally in said bevelled edges from said ends, a corner brace having legs each extending lengthwise in the channel of one of said bars, and a set screw passing through a transverse threaded

hole in each leg of said corner brace with its inner end engaging the bar in which the leg is located, said set screws extending substantially perpendicularly to the planes of said bevelled edges and diverging from each other outwardly from their inner ends whereby the mitered ends of the bars are forced into close contact by tightening said set screws.

6. A cabinet frame construction comprising frame bars extending at an angle to each other and having adjacent mitered ends and bevelled outer edges and having channels extending longitudinally in said bevelled edges from said ends, a corner brace having legs each extending lengthwise in the channel of one of said bars and having a bevelled edge substantially flush with the bevelled edge of said bar, and a threaded hole passing transversely through said leg from its bevelled edge, and a set screw in the hole in each of said legs and engaging the bar in which the leg is located, said set screws diverging from each other outwardly from their inner ends, whereby the adjacent ends of said bars are forced into close contact by tightening said set screws.

7. In a cabinet, a panel, a frame bar against which said panel is adapted to seat, a locking bar movable lengthwise in said panel and having a projecting flange adapted to enter a channel in said frame bar, said channel having an inwardly projecting mouth flange provided with a notch, and said locking bar having a lateral projection arranged to pass through said notch and having a bevelled end which engages with an edge of said notch and cams said projection into co-operating relation with said mouth flange to force said panel tightly against said seat face by the longitudinal movement of said locking bar in said channel.

8. In a cabinet, a panel having a bevelled edge, a frame bar having a bevelled edge against which said panel edge is adapted to seat, a locking bar movable lengthwise in said panel and having a projecting flange adapted to enter a channel in said frame bar, said channel having an inwardly projecting mouth flange provided with notches, said locking bar having lateral projections arranged to pass through said notches and each projection having a bevelled end, and means for moving said locking bar lengthwise, whereby the bevelled ends of said projections by engagement with ends of said notches act to cam said panel toward or from its seat as said projections pass within said channels and into abutting relation to said mouth flange.

9. A panel frame comprising a side frame bar and end frame bars, corner braces having legs secured in longitudinal channels in said bars, and a locking bar movable lengthwise in the channel of said side bar between said corner braces, said locking bar having reduced end extensions overlapping the adjacent legs of the corner braces and closing the spaces between the ends of the locking bar and the corner braces.
